UNITED STATES PATENT OFFICE.

TIM B. CRAM, OF CHICAGO, ILLINOIS, ASSIGNOR TO THE RAILWAY MATERIALS COMPANY, OF CHICAGO, ILLINOIS, A CORPORATION OF ILLINOIS.

APPARATUS FOR BURNING PULVERIZED FUEL.

1,258,654.

Specification of Letters Patent. Patented Mar. 12, 1918.

Application filed July 19, 1915. Serial No. 40,636.

To all whom it may concern:

Be it known that I, TIM B. CRAM, a citizen of the United States, residing at Chicago, in the county of Cook and State of Illinois, have invented certain new and useful Improvements in Apparatus for Burning Pulverized Fuel, of which the following is a specification.

This invention relates to an apparatus for 10 burning carbonaceous fuel and, while particularly adapted to the burning of pulverized solid fuel, it is applicable with good results to the burning of other forms of carbonaceous fuel.

15 It is the object of my invention to provide an apparatus which is particularly adapted for use in carrying out the method of burning carbonaceous fuel to produce a clear short flame of great heating power without 20 the smoke which is ordinarily incidental to short flame combustion.

A further object of my invention is the provision of an apparatus for burning carbonaceous fuel, the use of which obviates 25 the necessity of depending upon the radiation from the walls of the furnace to supply the heat necessary to bring the fuel to the ignition temperature, the heat being derived from the combustion of a portion of 30 the fuel itself.

Another object of my invention is the provision of an apparatus for burning pulverized solid fuel in which the fuel may be ignited directly by means of a torch without 35 the necessity of preheating the burner as has been necessary with furnaces of types heretofore known.

A still further object of my invention is the provision of an apparatus for burning 40 pulverized solid fuel which is so constructed that combustion is almost instantaneous and is practically completed at or near the junction of the combustion chamber of the burner with the furnace.

45 Still another object of my invention is the provision of means to prevent flame propagation between the pre-heating combustion chamber of the burner and the fuel supply nozzle, whereby the life of the metal parts is 50 materially prolonged.

Other objects and advantages of my invention will be apparent as it is better under-

stood by reference to the following specification when read in connection with the accompanying drawing, in which—

55

Figure 1 is an elevation partially in section of a furnace equipped with a burner according to my invention, together with a controller for supplying fuel thereto, and

Fig. 2 is an enlarged vertical section 60 through the burner.

Heretofore two methods of burning pulverized solid fuel have been known. The first is the long flame method and consists briefly in injecting pulverized fuel, mixed with a quantity of air, at a high velocity into a furnace chamber. This method is adapted only for use in long chambers such as the cement kiln. The combustion takes place only upon the outside of the cloud of fuel and the result is an elongated, cone flame. The second method is the so-called short flame method and it is to an apparatus particularly adapted for carrying out such a method that my invention relates. Heretofore short flame methods of burning pulverized solid fuel have been operated on the principle of mixing all of the combustion air with the fuel and injecting it in a diffused state into the furnace chamber. This produces a lazy smoky flame of low heating value, which is totally unadapted for most purposes and hence has met with no success in the practical art.

With the constantly rising price of fuel oil it is extremely desirable that apparatus be devised, whereby pulverized solid fuel, such as anthracite, bituminous coal, peat, etc., may be burned with a clear short flame such as is already possible to attain with oil burners.

Referring to the drawings, 1 designates a small forging furnace and is indicative merely of a large class of furnaces to which my invention is applicable and 2 designates generally the burner according to my invention, which is attached to one side of the furnace and is connected by means of a pipe 3 to a source of pulverized fuel, in this instance a controller 4. The pulverized fuel is drawn into the pipe 3 by means of an injector 5, supplied with air under pressure from a pipe 6 and controlled by a valve 7. Air is supplied to the burner through a pipe

8, connected to any suitable source of supply under pressure, and is controlled by a valve 9 in the pipe.

The burner comprises the walls 10, constructed of refractory material, such as fire-brick, and is supported in any suitable manner adjacent one side of the furnace 1, a metal bracket 11 being provided in this instance to support the burner. The burner 10 is provided with two distinct chambers 12 and 13, in this instance disposed normal to each other, which may be termed, respectively, the preheating and final combustion chambers, and a passage 14 of smaller cross-sectional area than the chamber 12, communicating with one end thereof and arranged substantially concentrically therewith. At the junction of the chamber 12 and the passage 14, the shoulder 15 is formed, the function of which will presently appear. It is to be understood that the chambers 12 and 13 and the passage 14 may be circular in section or of any other suitable form.

25 A nozzle 16 enters the end of the passage 14 remote from the shoulder 15 and is adapted to be connected to the pipe 3 to direct a jet of fuel into the passage 14 and the chamber 12. A member 17 surrounds the nozzle 16, providing an air passage concentric therewith, whereby a jacket of air is directed into the passage 14 and the chamber 12 surrounding the jet of fuel. The member 17 provides a duct 18 leading to the air supply pipe 8, the valve 9 being disposed at the junction of the duct 18 and the pipe 8, and adapted to control the air supply. A duct 19 leads from the duct 18 to a point adjacent the junction of the chambers 12 and 13 40 and is adapted to supply the final combustion air and to direct the resulting combustion products in the desired direction. The jet of air issuing from the duct 19 also acts as an injector to draw the fuel from the chamber 12. In the form of the burner disclosed in the accompanying drawing the jet of final combustion air from the duct 19 has a direction normal to the direction of the fuel jet, but it is to be understood that this 45 is merely illustrative and that it may be directed as desired. A lighting hole 20 is provided in the wall of the passage 14 adjacent the end of the nozzle and a suitable plug 21 is normally disposed therein.

50 The method of operation is as follows: The pulverized solid fuel is drawn from the controller 4 into the pipe 3 by means of the injector 5 and is forced in the form of a fuel cloud, with the solid particles suspended in a limited quantity of air, into the nozzle 16 and thence into the passage 14 and the chamber 12 in the form of a jet. The valve 7 may be set to deliver the desired quantity of fuel at the required velocity to the nozzle. 55 It may be noted that the best results are ob-

tained when the fuel is finely pulverized so that approximately 95% would pass through a 200-mesh screen and when it is delivered at a velocity of approximately 4500 feet per minute. This insures the proper suspension 70 of the fuel in the air and prevents clogging of the pipes and the nozzle. The valve 9 is then operated to admit air through the ducts 18 and 19 to the burner and a torch is applied outside the lighting hole 20 and the 75 flame is drawn into the chamber 12 to ignite the fuel in the preheating combustion chamber. Ignition will take place instantaneously, exactly as in the case of gas or oil, it being unnecessary to preheat the burner, 80 according to the usual practice with pulverized solid fuel burners. Ignition will take place only within the chamber 12 since flame propagation rearwardly of the shoulder 15 is prevented thereby, and the passage 14 and the metallic members 16 and 17 85 remain cool through the entire operation of the furnace.

The velocity of the air should be slightly in excess of the velocity of the fuel jet and 90 by reason of the difference in velocities the air of the jacket surrounding the fuel jet draws particles of fuel away from the edges thereof and the arrangement of the chamber 12 is such that these particles whirl away 95 from the jet, as indicated in Fig. 2 of the drawing, owing to the tendency of the fuel and air jets to reduce the pressure near the walls of the chamber. This causes the particles of fuel to become thoroughly mixed with 100 the air to form a combustible mixture, which burns when ignited and preheats the remainder of the fuel in the jet as it passes downwardly to the final combustion chamber 13. The fuel of the jet during its travel to 105 the final combustion chamber 13 is preheated to the ignition point and at the lower end of the chamber 12 it meets the jet of air from the duct 19, which is sufficient in 110 quantity to complete the combustion of the fuel. Combustion is almost instantaneous, being practically complete at the entrance of the furnace and the incandescent combustion products pass into the furnace in the form of a clear, short and very hot flame. 115

It will be seen from the foregoing that I have devised a novel apparatus for burning carbonaceous fuel, whereby a short flame free from smoke may be produced. The apparatus possesses an advantage in addition to its adaptability to the method described in that the metal parts may be kept cool without water-jacketing or other artificial cooling means and the life of the parts is correspondingly longer and the burner is 120 less expensive to maintain.

It will be obvious that various changes may be made in the form, construction and arrangement of the parts without departing from the spirit and scope of the invention 130

or sacrificing any of its material advantages, the form hereinbefore described being thereby a preferred embodiment thereof.

I claim:

- 5 1. In a fuel burner, the combination of walls of refractory material forming an elongated combustion chamber and a concentrically arranged passage of smaller cross-sectional area leading thereto, said walls providing an abrupt imperforate shoulder at the juncture of said chamber and passage, a nozzle at the end of said passage remote from said shoulder for injecting fuel into said passage and chamber forming a fuel jet, and an inlet concentric with said nozzle and ending in the plane of the end thereof to supply a surrounding jacket of air to support a limited combustion of said fuel, said shoulder being adapted to prevent flame propagation rearwardly thereof and to assist in causing eddy currents about said fuel jet whereby a portion of the fuel is withdrawn from the jet and mixed with the surrounding air.
- 10 15 20 25 2. In a fuel burner, the combination of walls of refractory material forming an elongated combustion chamber and a concentrically arranged passage of smaller cross-sectional area leading thereto, said walls providing an abrupt imperforate shoulder at the juncture of said chamber and passage, a nozzle at the end of said passage remote from said shoulder for injecting fuel into said passage and chamber forming a fuel jet, and an inlet concentric with said nozzle and ending in the plane of the end thereof to supply a surrounding jacket of air to support a limited combustion of said fuel, said shoulder being adapted to prevent flame propagation rearwardly thereof and to assist in causing eddy currents about said fuel jet whereby a portion of the fuel is withdrawn from the jet and mixed with the surrounding air.
